COLLAPSIBLE TOILET ARTICLE

Kingsley F. Horton and Lyman F. Higbee,
Syracuse, N. Y.

Application April 27, 1936, Serial No. 76,648

5 Claims. (Cl. 15—184)

This invention relates to a collapsible toilet article such as a tooth brush or the like, wherein a case for the toilet implement is adapted to function as a handle or holder during the use of the implement.

A collapsible tooth brush adapted to be carried in a purse or hand bag or in a garment pocket usually comprises an attachment member connected with the brush adapted to frictionally engage the case for maintaining the brush in the case. This attachment member, when the brush is mounted in the case, extends a considerable distance outwardly beyond the case so as to form a handle of sufficient length to enable the user to obtain a firm finger grip thereon whereby the brush may be readily removed from the case. Such attachment members are not only unsightly but also add to the overall length of the assembled parts to such an extent as to often render the article too large to be carried in a small purse or pocket, or to necessitate the use of a miniature brush or implement.

The main object of this invention is to overcome the above mentioned objection by providing a collapsible tooth brush or similar implement having a removable case or holder therefor with an attachment member for frictionally holding the brush or implement in the case that is simple in construction and operation and which, when assembled with the case or holder, will extend but a relatively short distance beyond the case, thereby producing an article which is very compact to enable the same to be easily carried in a small purse or pocket and at the same time be attractive in appearance.

In carrying out the above mentioned objects, we have provided a novel friction attachment member or head which, when assembled with a brush or other implement in a suitable case or holder will extend only slightly outwardly beyond said case. This attachment head is provided with a cam surface which is so related to the open end portion of the case that when a relatively slight lateral pressure is exerted upon the exposed portion of the attachment head, said cam surface will effect release of the frictional engagement of the head with the case and produce an initial outward movement of the head and brush relative to the case. The head and brush may thereafter be readily removed from the case by using the increased exposed portion of the head as a handle.

These and other objects and advantages pertaining to the invention will more readily be

understood from the following description taken in connection with the accompanying drawing in which:

Figure 1 is a perspective view illustrating a collapsible tooth brush embodying the various features of this invention with the parts thereof in the assembled position. 5

Figure 2 is a perspective view of the device shown in Figure 1 showing the parts thereof in disassembled relation. 10

Figure 3 is a perspective view of the device shown in Figure 1 with the brush and holder shown in the extended relation ready for use.

Figure 4 is an enlarged longitudinal sectional view of the case or handle with the tooth brush mounted therein. 15

Figure 5 is an enlarged detail transverse sectional view taken substantially on line 5—5, Figure 3.

Figure 6 is a perspective view illustrating the initial step taken in effecting the release of the tooth brush or other implement from the case or holder. 20

In the structure shown in the drawing we have illustrated a tooth brush 1 comprising a substantially rectangular body portion or back member 2 and a reduced shank portion 3. The body portion is provided with bristles 4 secured thereto in any suitable manner to extend outwardly from one side thereof. The opposite side 2' of the body member is slightly curved longitudinally from the central portion inwardly towards the ends thereof as shown in Figure 4. 25

To the outer end of the shank 3 is secured an attachment head 5 which, in this instance, is substantially rectangular in cross section and is adapted to extend into a case 6 which has one end closed and the other end thereof open for receiving the brush and attachment head therein. The interior or chamber 7 of the case 6 is substantially rectangular in cross section and is of substantially the same cross sectional area throughout the length thereof, the width of the chamber 7 being slightly greater than that of the brush body 2 so as to permit said body to readily move into and out of the chamber. The height of chamber 7 is substantially equal to the distance between the outer curved surface 2' of the body member 2 and the outer ends of the bristles 4 so that when the brush is in the case chamber, the outer curved surface of the body member will be maintained in contact with the wall of the chamber 7 by the bristles 4. 30

The attachment head 5 is provided with upper and lower sides 9 and 10 respectively which ex-

tend in substantially longitudinal parallel relation with each other and the distance between these sides is substantially equal to or slightly less than that of the longer transverse axis of the chamber 7. The shank 8 is preferably an arcuate member as shown in Figure 4 and is so attached to the head 5 that the upper surface 9 of the attachment head is normally maintained thereby in a plane above that of the outer curved surface 2' of the body member 2 so that when the brush is mounted in the case chamber, the attachment head will be yieldingly urged by the co-action of the body member 2 and bristles 4 with the walls of the chamber toward the wall 15 of said chamber adjacent side 9 for a purpose hereinafter described. The other longitudinal side 10 of the attachment head is provided with an undercut portion extending from intermediate the ends of the head inwardly and toward the 20 inner end of the head to form an arcuate cam surface 11 which, when the brush is fully inserted into the case chamber, has the forward end thereof substantially in alignment with the end of case 6 as shown in Figure 4. This cam 11 is preferably a concave surface arranged with the cord thereof extending at an acute angle of substantially 30° to the transverse plane of the head extending through the longitudinal axis thereof. Said cam surface thus extends abruptly 25 inwardly from the outer end of the case so that when head 5 is moved laterally of case 6 in the direction of cam 11, said cam will be brought into sliding engagement with the adjacent wall of the chamber 7 at the open end of the case and 30 produce axial movement of said head and the brush 1 relative to the case 6.

The opposite side surfaces as 13 and 14 of the attachment head 5 have the central portions thereof, that is, the portions substantially midway between the outer and inner ends of the head, spaced apart a distance slightly greater than the 40 length of the shorter transverse axis of the case chamber 7. These sides 13 and 14 taper in opposite directions from these central portions 45 thereof inwardly toward each other so that the sides 13 and 14 at the inner and outer ends of the head are spaced apart a distance slightly less than the length of said transverse axis of chamber 7. It will now be readily understood that the 50 attachment head 5 is adapted to have its ends interchangeably extended into the case 1 while the intermediate portion of the sides 13 and 14 of said head will frictionally engage the wall of the case chamber 7 adjacent the open end thereof 55 of for releasably maintaining the head and the brush member 1 attached thereto connected with the case 6.

It will now be observed that the attachment head 5 is a relatively short member which is so related to the brush 1 that when said brush and head are mounted in the case 6, the head will project outwardly only a relatively short distance beyond the open end of the case and, therefore, does not provide a gripping surface to enable the 60 user to obtain a firm hold thereupon sufficient to easily overcome the friction between the attachment head and case 6 and thereby enable the brush to be withdrawn from the case. However, in our novel construction, when it is desired to 65 remove the brush from the case, this may be readily accomplished in the manner illustrated in Figure 6 by holding the case in the palm of the hand with the side 9 of the attachment head adjacent the thumb and then pressing with the 70 thumb upon the exposed surface 9 to move the 75

head laterally in the direction toward the side 10 and cam 11 thereof against the lateral stress on said head produced by the co-action of the body portion 2 and bristles 4 and inner wall of the chamber 7 as hereinbefore described. This latter movement of the head will cause the cam to engage the outer end portion of the case and slide therealong to effect an initial outward axial movement of the head and brush relative to the case. This axial movement is sufficient to move the 10 head out of frictional engagement with the case and provide an ample gripping surface by which said brush may be thereafter readily removed from the case. In order that the user may readily determine which side of the exposed surface of 15 the attachment head 5 to engage with the thumb, we have provided the outer end portion of side 9 with a slight recess 17 which may be of contrasting color to that of said head.

It will now be apparent that the tension produced upon the brush 1 when the head 5 is moved into the case chamber 7, due to the offset relation of the head with the brush, will yieldingly maintain the cam 11 out of engagement with the case 6 and thereby prevent to a degree the head 25 and brush being accidentally removed from the case.

Although the device shown and described is particularly simple in construction and operation, we do not wish to be limited to the exact 30 construction shown as it is obvious that various changes may be made in the form and relation of the parts thereof without departing from the spirit of the invention as set forth in the appended claims.

We claim:

1. A toilet article comprising an implement, a hollow holder having an open end adapted to receive the implement therein, an attachment head connected with the implement adapted to 40 extend into said holder in frictional engagement therewith and with the outer end thereof projecting a relatively short distance beyond said open end, said attachment head having a cam surface normally positioned out of engagement 45 with the holder and adapted to slidably contact with the holder upon relative lateral movement of the head and holder for producing outward axial movement of the head and implement relative to the holder.

2. A collapsible instrument of the class described comprising a toilet implement, an open ended case member for removably receiving the implement therein, and an attachment member connected with the implement and adapted to have its ends interchangeably and frictionally engaged in the open end of the case member, said attachment member being provided with an undercut portion extending from intermediate its ends inwardly and toward one of said ends to 60 form a cam surface normally spaced from and aligned with said open end of the case when the attachment member is mounted in the case for sliding contact therewith to produce outward movement of the attachment member and implement upon relative lateral movement of said attachment member and case.

3. A collapsible instrument of the class described comprising a toilet implement, an open end case member for removably receiving the 70 implement therein, and an attachment head for the implement adapted to extend into said case, said head and the interior of said case being substantially rectangular in cross section, said head having a pair of substantially parallel opposed 75

5 sides adapted to readily enter the open end of the case and a second pair of opposed sides having tapered portions adapted to frictionally engage said open end, one of said parallel sides of the head having a cam surface extending longitudinally thereof out of engagement with the case and with one end of said surface arranged in registration with the open end of the case to slidably contact with the case at said open end upon relative lateral movement of the head and case for producing outward axial movement of the head and implement relative to the case.

10 4. A collapsible tooth brush comprising an elongated body member having an arcuate back surface and bristles extending outwardly from the opposite surface thereof, an attachment head connected with the body member, a hollow holder having an open end adapted to receive the body member and at least a portion of the attachment member therein, said attachment member having a longitudinal surface normally positioned a short distance inwardly from the plane of said back surface, the opposite side of said attachment member being provided with an undercut portion to form an abrupt cam surface adapted to contact with said open end of the holder when the attachment member is mounted in the holder for producing outward movement of the head and brush, the interior of the holder being substantially uniform in cross sectional area throughout the length thereof and substan-

tially equal to the cross sectional area of the body member and bristles for engagement therewith whereby the attachment member will be urged in a direction to maintain said cam surface from contacting said end portion of the holder.
